C. L. GOODRUM.
MACHINE SWITCHING DEVICE.
APPLICATION FILED FEB. 24, 1919.

1,438,758.

Patented Dec. 12, 1922.

UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

MACHINE SWITCHING DEVICE.

Application filed February 24, 1919. Serial No. 273,926.

To all whom it may concern:

Be it known that I, CHARLES L. GOODRUM, a citizen of the United States, residing at New York, in the county of New York, 5 State of New York, have invented certain new and useful Improvements in Machine Switching Devices, of which the following is a full, clear, concise, and exact description.

This invention relates to telephone switching systems, and more particularly to a telephone switching system of the automatic or semi-automatic type in which the brush setting operation is controlled by power driven mechanism.

15 The object of this invention is to provide an organization of apparatus and circuits in a system of this class, whereby the period of operation of the apparatus, in completing a call between the calling and called subscribers' lines, may be reduced to a minimum.

Features of the invention are the provision of a register device controlled by impulses from the substation sender, and a 25 power driven switch, which is started simultaneously with the beginning of the first train of impulses, and is operated in accordance with the movement of the register, the arrangement being such that the switch can 30 keep pace with the impulses sent, but never advance beyond a corresponding position of the register until the trunk hunting stage of operation is reached.

This may be accomplished by means of a 35 register mechanism operated in response to impulses from the calling station and controlling in its operation the simultaneous operation of the brush carriage. The register preferably comprises a contact carrying 40 cylinder operated step by step in response to calling impulses, and having a contact surface over which a brush or contact carried by the brush shaft is moved to control the operating circuit of the power driven 45 mechanism which operates the brush carriage.

The drawing is a diagrammatic view of 50 the circuit organization, in which the brush carriage apparatus and the register are illustrated schematically.

The brush carriage of this invention may be similar to that shown in Patent No. 1,123,696, except that in this invention a

brush tripping shaft 5 is provided with a plurality of angularly displaced fingers 55 6-6 which are set in response to the operation of a stepping magnet 7 to a position to engage a right angularly extending end 8 on a brush tripping lever 9 to trip the brushes 10, 11, 12 and 13 when a shaft 14, 60 upon which these brushes are carried, is moved upwardly.

The register mechanism through which the brush carriage movement is controlled simultaneously with the sending of impulses 65 from the calling substation, comprises an insulating cylinder 16 upon which is mounted a conducting plate 17 having a stepped or staggered edge formed by cutting away portions thereof, in accordance with the 70 group arrangement of the contact banks. The rotation of this register is controlled through the agency of a stepping magnet 20 which is actuated in response to calling impulses from the calling station, as will 75 hereinafter more fully appear.

In the operation of the system embodying features of this invention, a subscriber A, in initiating a call by removing his receiver from the switchhook, will have his 80 line automatically connected with a trunk line through the agency of a line finder switch diagrammatically indicated at 25. When the subscriber's line is connected to the trunk, a double wound relay 26 pulls up 85 and completes a circuit for a slow release relay 27. The operation of the dial 28 at subscriber station A intermittently opens and closes the circuit of the double wound relay 26, and its armature upon each retraction completes a circuit for a brush-selecting magnet 7 which is operated to rotate the brush-selecting shaft 5 to bring a finger 6 thereon in position to trip a selected set of brushes. This operating circuit will be 95 from battery 30, through the winding of the magnet 7, over conductor 31, through the first contact of side-switch arm 32, through front contact and armature of the relay 27 and through the back contact and armature 100 of the relay 26, to ground. A circuit is also completed for a relay 33 which holds energized a slow release escape magnet 34.

Upon the termination of the first series of impulses, relay 26 remains energized and 105 33 remains deenergized, thereby opening the

circuit of the escape magnet 34, causing its deenergization and permitting it to move its wipers into their second position.

The subscriber now again operates the dial 28, and upon the first retraction of the armature of relay 26, a circuit is completed from battery, through the register or group selecting magnet 20, over conductor 35, side-switch arm 32 in its second position, front contact and armature of relay 27, and back contact and armature of relay 26, to ground. Upon a continued operation of the sending dial, impulses will be sent through the controlling magnet 20 to rotate the drum or cylinder 16. The conducting plate 17 on the cylinder 16 is connected with ground which, upon the first rotary step of the cylinder 16, will be connected through the brush or wiper 91 with a circuit which includes an up-drive magnet 40 of the brush carriage. This circuit will be from battery, through up-drive magnet 40, conductor 41, conductor 42, brush 91, and contact plate 17, to ground. On the completion of this circuit the brush carriage shaft 14 will move upwardly until the wiper 91 thereon moves from the conducting plate 17 onto a portion of the insulating cylinder 16. At or before this time, however, another impulse from the calling station will have been received to operate the controlling magnet 20 to rotate the cylinder and bring another step of the contact plate 17 into engagement with the wiper 91. This will cause the brushes to move over the second group of trunks. The operation is continued until the desired group has been selected and the impulses from the calling station have ceased, when relay 26 again remains energized, relay 33 drops off and opens the circuit of the slow release escape magnet 34, thereby causing the side-switch arm to move into position No. 3, providing the contact upon which the brushes are now resting is not busy. In this particular system the test contact of the busy trunk is not connected to ground, and thus no circuit is completed through test relay 45 when the test brush steps upon a contact which is busy. The slow release escape magnet 34 is therefore maintained in an energized condition over a circuit including battery, right-hand winding of escape magnet 34, side-switch wiper 46 in its second position, conductor 47, back contact and armature of relay 45, conductor 70, contact 71, closed in the off-normal position of cylinder 16 conductor 72, and back contact and armature of relay 33, to ground. The hunting movement of the brushes is therefore continued due to the closure of the circuit extending from grounded battery, winding of up-drive power magnet 40, conductor 41, side switch arm 46 in its second position, conductor 47, armature and back contact of relay 45, conductor 70, contact

71, conductor 72, armature and back contact of relay 33 to ground until the test brush 13 finds a grounded contact, whereupon the circuit or relay 45 will be completed from battery, over conductor 48, through side-switch arm 49, over conductor 50, and through test brush 13, to ground. Upon the energization of 45 the escape magnet 34 is deenergized to move the side-switch arms into position No. 3, thereby completing the circuit from the calling subscriber's line to the trunk over which the called subscriber is to be connected.

Upon the first step of the brush stepping magnet 7, a circuit is completed for relay 51 from battery, through back contact of relay 51, through contact 52 of the stepping magnet, to ground. Relay 51 is pulled up over this circuit, and completes a locking circuit for itself through an off-normal contact 18 of the brush tripping shaft 5. In the normal operation of the switch, a holding magnet 53 for releasing the brush tripping spindle 5 is operated to restore the spindle when the switch shaft 14 moves from normal position and closes contact 54. Should it occur, however, that the subscriber abandons the call during the first series of impulses, the circuit for 53 will be completed through the left outermost contacts of 51, 95 back contact of 27, and back contact of 26.

The switch is released by placing a direct ground upon the brush 9 which completes a circuit for the down-drive magnet 55 from battery, through the winding of the 100 down-drive magnet, over conductor 56, through side-switch wiper 57 in its third position and over conductor 50, to the grounded brush. Down-drive magnet 55, in pulling up, retracts a holding pawl 58, and completes a locking circuit for itself through an off-normal contact 59 which will be maintained until the brush shaft 14 is returned to its normal position.

When the brush shaft 14 reaches its normal position, a projection 60 thereon engages the tail of a holding pawl 61 to release the register cylinder 16, thereby permitting it to return to its normal position.

Should it happen that the brushes get 115 ahead of the register, they will be delayed momentarily until the register makes a succeeding step unless they are in the group in which hunting is to take place, in which case they may come to rest on the idle trunk 120 before the change-over occurs. On the other hand, if the brushes are behind the movement of the register, they will complete their operation.

What is claimed is:

1. In a telephone switching system, a subscriber's impulse sending mechanism, a step-by-step register device responsive to impulses from said impulse sending mechanism; a power driven selector switch, a

driving circuit for said selector switch established at each step of said register device, and means to insure correct positioning of said switch at any relative speed of operation of said step-by-step device.

2. In a telephone switching system, a subscriber's impulse sending mechanism, a power driven selector switch, register means operated directly by said impulse sending means and adapted in its operation to cause the operation of said selector switch simultaneously with the operation of said sending mechanism and in synchronism therewith, and means to insure correct positioning of said switch at any relative speed of operation of said register means.

3. In a telephone switching system, a subscriber's impulse sending mechanism, a registering device, a power driven selector switch selectively operated in accordance with the position of said register, a brush movable by said selector switch, a driving circuit for said selector switch extending through said movable brush, and means to close said driving circuit successively in accordance with the positioning of said register.

4. In a telephone switching system, a subscriber's impulse sending mechanism, a power driven selector switch, a registering device, means to position said register device in response to actuation of said impulse sending mechanism, means to initiate operation of said selector switch as soon as said impulse sending mechanism is actu-

ated, means to selectively operate said selector switch in accordance with the setting of said register, and means to insure correct positioning of said switch at any relative speed of operation of said register.

5. In a telephone switching system, a subscriber's impulse sending mechanism, a step-by-step register device responsive to impulses from said impulse sending mechanism, a power driven selector switch operated in response to the operation of said register device and simultaneously with the operation of said impulse sending mechanism to move its brushes over a terminal group for each impulse of the impulse sending mechanism, and means to insure correct positioning of said switch at any relative speed of operation of said step-by-step device.

6. In a telephone switching system, a subscriber's impulse sending mechanism, a step-by-step register device responsive to impulses from said impulse sending mechanism and having a staggered or stepped contact surface, a power driven selector switch having a wiper thereon adapted to cooperate with the contact surface of said step-by-step register, and an operating circuit for said switch controlled through the engagement of said wiper with said contact surface.

In witness whereof, I hereunto subscribe my name this 18th day of February A. D., 1919.

CHARLES L. GOODRUM.
